Inventor:
Kenneth J. Tobin

UNITED STATES PATENT OFFICE.

KENNETH JOSEPH TOBIN, OF CHICAGO, ILLINOIS.

SLIDING-DOOR HANGER.

1,373,684.

Specification of Letters Patent. Patented Apr. 5, 1921.

Application filed April 2, 1920. Serial No. 370,662.

To all whom it may concern:

Be it known that I, KENNETH J. TOBIN, a citizen of the United States, residing at Chicago, in the county of Cook and State of Illinois, have invented certain new and useful Improvements in Sliding-Door Hangers, of which the following is a full, clear, and exact specification.

My invention relates to door hangers of the sliding door type and particularly to an improved hanger and track wherein the hanger is adjustable both vertically and laterally to compensate for irregularities due to warping or settling of the building or car to which my invention is applied.

One object of my invention is to provide a door hanger comprising a series of fixed brackets secured to the building or car and carrying adjustable rollers, the door being suspended thereon by a track or hanger, which is formed to partly embrace the rollers, the bottom of said door being guided by a series of roller guides to insure ease of operation.

Another object is to provide a door hanger that will afford a wide range of adjustment both vertically and laterally relative to its support without disarrangement of the track.

Still another object is to provide a door hanger that comprises a series of adjustable rollers and a coöperating track secured to the door in such a manner that the door cannot be removed or disarranged during operation or until one or more of the adjustable rollers are removed from the fixed brackets.

Still another object is to provide a door hanger that comprises a series of adjustable rollers supported by independent fixed brackets, the said rollers being adjustable both vertically and laterally, both adjustments being accomplished by a single adjusting means.

Still another object is to provide a door hanger of the described type embodying a series of fixed brackets carrying adjustable rollers and each bracket provided with a watershed.

With the above and other objects in view, my invention consists in the construction, combination and arrangement of parts hereinafter described, claimed and illustrated in the accompanying drawings in which—

55 Figure 1 is a fragmentary front elevation

of a wall and door with my invention applied thereto.

Fig. 2 is a partial vertical section on an enlarged scale taken on line A—A of Fig. 1.

Fig. 3 is a detail view of one of the brackets equipped with the adjustable roller and watershed constituting a complete fixture or unit.

Fig. 4 is a side view of a bracket partly in section, the dotted lines showing the manner in which the roller may be vertically adjusted.

Fig. 5 is a plan view of a bracket, the dotted lines showing the manner in which the roller may be laterally adjusted.

Fig. 6 is a sectional detail view of the upper part of the roller post.

Fig. 7 is a similar view of a modified construction, and

Fig. 8 is a detail view of a modified construction of track or hanger mounting.

In the embodiment illustrated by the drawings, my invention is shown in connection with the usual wall 10 having secured thereto, in any well-known manner, the fixed brackets 11, said brackets having an outwardly projecting horizontal portion 12 formed with a transversely extending slot 13 adjusted to receive the threaded post 14. At the upper end of said post is a head portion 15 which is preferably recessed cup-shaped as shown at 15^a to receive the ball or roller 16. The ball 16 is placed in the recess 15^a which is made to a depth slightly below the center of the ball or roller 16 so that said ball may be loosely secured from being displaced during transit or operation by peening over the edge of the head portion 15, as shown at 17 (Fig. 6).

The threaded post 14 passes through the slot 13 in the bracket 11 and is adjustably secured thereto by the usual nuts 18 and 18^a, one above the projecting portion 12 of the fixed bracket 11 and the other below.

It is evident from the structure just described that loosening nuts 18 and 18^a permit the threaded post 14 to be adjusted vertically and may also be adjusted laterally by sliding the threaded post 14 to any position within the limits of the transversely extending slot 13 formed in the outwardly projecting horizontal portion 12 of the fixed bracket 11. It is also evident that both adjustments may be accomplished by a single adjustment means and locked in the desired

adjustment by drawing the lower nut 18^a securely to the lower surface of the horizontally projecting portion 12 of the bracket 11.

Each bracket is preferably furnished with 5 a watershed 19, in this case a plate or stamping which may be of the form shown in Figs. 2 and 3.

The track or hanger may be composed of 10 a single plate 20, which extends the entire width of the door 21 and is attached thereto in any preferred manner as by bolts or screws extending through the flat portion 22 thereof. The upper portion of the plate is bent outwardly just above the upper edge of 15 the door as at 23 and then upwardly and inwardly to form a substantial horizontal bracket engaging portion 24. This portion 24 is preferably formed with a depression or groove 25 constituting a track or runway 20 for the rollers 16 and the inner edge is bent downwardly as at 26 to form a retaining flange which prevents the track from leaving the brackets.

Fig. 7 is a modification of the construction shown in Fig. 6 wherein a cap C secured 25 to the head 15^b serves to retain the ball or roller instead of peening as described in Fig. 6.

In Fig. 8, I have shown a modified form 30 where instead of using a single sheet or plate I employ separate castings 27 secured to the door 21 as by bolts 28 and shaped substantially in the same manner as the plate 20. The hooked or curved upper portion 29 35 is formed to receive a track 30 having a roller channel 31 substantially as the construction above described and shown in Fig. 2 and engaging the brackets in the same manner.

The plurality of fixed brackets carrying a 40 plurality of adjustable rollers together with roller engaging hanger mechanism which form the principal features of the present invention will now be described:

A plurality of units consisting of the 45 bracket, post, roller, adjusting nuts and watershed are fixed to the wall of a building or car in substantial alinement preferably with one of the rollers intermediate the plurality being omitted to allow the hanger 50 to be admitted after which the roller is replaced thereby making it impossible to remove the door during its normal operation.

It is also evident from the construction heretofore described that the door can be 55 adjusted to allow for warping of the walls due to weather conditions and in the case where it is applied to a box car or the like, it serves to overcome binding and sagging due to accidents because of the slight possibility of all the fixtures being damaged at 60 one time.

Heretofore when an accident occurred to a car equipped with the style of track that was attached to the car instead of the door, any 65 slight dent or depression in the length of the

track would cause the door to bind or stop intermediate its length of travel and its adjusting features rendered useless thereby causing considerable waste of time and labor and frequently a total loss to the fixture. 70 I overcome the above difficulty by minimizing and confining to certain locations the mechanism that could be damaged from the above described causes.

It is also evident that from the nature of 75 the above described fixtures or units, the roller members can be adjusted to a slight pitch which would serve to cause the door to open or close of its own weight, proving a valuable asset in the case of elevator doors 80 and warehouse fire doors.

It is also evident that by the use of a plurality of units any one of the parts thereof may be replaced with little outlay of expense or labor. Another important feature 85 of the above described arrangement being the minimizing of the amount of hanger or track heretofore necessary and also in greatly reducing the necessary watershed as far as cost and bulkiness is concerned. 90

It will readily be seen from the above disclosure that a very simple and efficient construction has been provided and a construction whereby a plurality of adjustable units and coöperating parts does away with the 95 necessity of accurate castings and hanger track heretofore necessary.

While I have in the above specification described one embodiment which my invention may assume, it should be understood that it 100 is capable of modification and can be applied to barns, cars, warehouses, garages, elevators, rolling ladders, overhead carriers, etc., and that such modifications may be made without departing from the spirit and 105 scope of the invention as expressed in the following claims:

1. In hanger construction, the combination of a series of spaced brackets each provided with a bearing roller and a track bridging 110 the space between said brackets and formed with a portion supported on said rollers and shaped to be self retaining thereon.

2. In hanger construction, the combination of a series of alined brackets each provided with a vertical post carrying a ball bearing and a movable element suspended on said brackets by a track overhanging said posts and formed with a groove engaging 115 said bearings, the overhanging portion of 120 said track terminating in a depending flange.

3. In hanger construction, the combination of a series of alined brackets each provided with an apertured shelf, a post mounted in each aperture and having a socket on its 125 end, a ball rotatably mounted in said socket, and a movable element suspended on said brackets by a track overhanging said posts and formed with a groove engaging said balls.

4. A fixture for sliding doors comprising a bracket adapted to be secured to a support, and having a slot therein, a post engaging in said slot and carrying a roller at one end, 5 the post being adjustable both horizontally and vertically in the slot, and means for securing the post in adjusted position.
5. A fixture for sliding doors comprising a bracket adapted to be secured to a support 10 and having a horizontal projecting shelf, an adjustable post engaging in a slot in said shelf, a roller supported by one end of the post, adjusting means carried by the other end of the post whereby the post and roller 15 may be adjusted both horizontally and vertically in the slot.
6. A fixture for sliding doors comprising a bracket adapted to be secured to a support, and having a slot therein, a post engaging in said slot and carrying a roller at one end, 20 the post being adjustable both horizontally and vertically in the slot, and means for securing the post in adjusted position, and a water shed adapted to be secured to the bracket and projecting over the post and 25 roller.
7. A hanger bracket comprising a vertical portion, a shelf portion, a roller supporting post mounted on the shelf portion, and a water shed secured to the vertical portion 30 and extending outwardly and downwardly above the post.

In testimony whereof I affix my signature.
KENNETH JOSEPH TOBIN.
